Augustine B. Straighton.

ATTORNEY

UNITED STATES PATENT OFFICE.

JOSEPH H. RUSBY, OF NUTLEY, NEW JERSEY.

BREAST-DRILL.

1,268,157.

Specification of Letters Patent. Patented June 4, 1918.

Application filed June 1, 1917. Serial No. 172,166.

To all whom it may concern:

Be it known that I, JOSEPH H. RUSBY, a citizen of the United States, and a resident of Nutley, in the county of Essex and State 5 of New Jersey, have invented certain new and useful Improvements in Breast-Drills, of which the following is a specification.

The principal objects of the present invention are, first, to provide for accommodating the handle, as well as the breast plate, of a drill to such obstructions as may and frequently do occur in practice, so that the drill can be used with either of these parts in such different positions as may be most 10 convenient, second, to provide for readily positioning the handle in normal position, and third, to provide comparatively simple strong and efficient means for accomplishing these results.

20 The invention will be claimed at the end hereof, but will be first described in connection with the embodiment of it chosen for illustration in the accompanying drawings, in which—

25 Figure 1, is a view, partly in longitudinal section, of a drill embodying features of the invention, showing parts in unclamped relation.

Fig. 2, is a sectional view, drawn to an enlarged scale, and illustrating parts in clamped relation, and

Fig. 3, is a transverse section through the handle.

In the drawings 1 is a tubular frame externally provided with a circumferential rib 2, and with a cylindrical seat 3, having a flat 4. 5, is a breast plate having a tubular shank 6, rotatably and detachably mounted in the tubular end of the frame.

40 7, is a collar rotatable on the collar-seat 3, of the frame and having one of its ends rolled or crimped around the rib 2, so as to permit rotary motion and prevent endwise motion of the collar. The collar 7, at its 45 other end is provided with a contracted flange 8, through which the shank 6 passes and by the rim wall of which the shank may be clamped. 9, is a handle screwed radi-

ally through the collar 7, or more accurately through a boss 10, thereon, and its end is 50 adapted to press upon the collar-seat 3. Since the shank 6 is tubular it accommodates the end portion of the spindle 11.

In use the end of the handle 9 usually presses upon the flat 4 and causes the flange 55 rim of the collar to clamp the breast plate shank, so that both the handle and breast plate are immovable in respect to the frame 1. However by unscrewing the handle sufficiently to free its end from pressing engagement with the flat 4, or other part of the seat 3, the handle and collar can be turned into and clamped in any radial position that may be most convenient, and this can be done by the hand which engages the 60 handle. Whenever the handle is screwed home against the collar-seat the breast plate is clamped and held against turning by the 65 rim of the collar flange.

What I claim is:

1. In a drill the combination of a tubular frame provided with a collar seat, a breast plate having a shank turnably mounted in the frame, a collar mounted for rotation and not for end movement on said seat and 75 adapted to engage and disengage said shank, and a handle screwable radially through the collar into engagement with the frame to cause the collar to clamp and unclamp the parts.

2. In a drill the combination of a tubular frame provided externally with a circumferential rib and with a cylindrical collar seat, a breast plate having a tubular shank rotatively mounted in the frame, a collar rotatable on the collar seat in engagement with the rib and having a contracted flange through which the shank extends and by the rim wall of which the shank may be clamped, and a handle screwed radially through the 85 collar and having its end adapted to engage the frame to clamp and unclamp said parts.

In testimony that I claim the foregoing I hereto set my hand this 29th day of May, 1917.

JOSEPH H. RUSBY.
